CLAIM

The ornamental design for a golf club indicator device, as shown and described.

DESCRIPTION

FIG. 1 is a rear perspective view of a golf club indicator device showing our new design with the signal flag extended;

FIG. 2 is a rear perspective view similar to FIG. 1 with the signal flag retracted;

FIG. 3 is a top plan view of FIG. 1;

FIG. 4 is a bottom plan view of FIG. 1;

FIG. 5 is a front elevation view of FIG. 1;

FIG. 6 is a rear elevation view thereof;

FIG. 7 is a right side elevation view thereof; and,

FIG. 8 is a left side elevation view thereof.
